CAR ROOF

Charles David Bonsall, Pittsburgh, Pa., assignor
to P. H. Murphy Company, New Kensington,
Pa., a corporation of Pennsylvania

Application March 3, 1933, Serial No. 659,493

7 Claims. (Cl. 108—5.4)

This invention relates to car roofs of the kind wherein the metal roof sheets are fixed in place. Heretofore, the common practice has been to fix the sheets by riveting, which requires accurately 5 locating and punching the rivet holes and squaring the edges of the sheets preliminary thereto and leaving a "lap" along the margin beyond the line of rivets. In some such roofs, the marginal portions of the sheets were shaped and in position to take care of a considerable portion of 10 the stresses in the structure but were likely to act inefficiently due to buckling of their edges. The principal objects of the present invention are to save the metal heretofore required for the 15 laps, dispense with the operations of squaring the sides, locating and punching the rivet holes, dispense with accurate matching of sheets, and otherwise simplify manufacture and assembly, produce stronger and tighter joints, and render 20 the marginal portions of the sheets fully effective in taking care of stresses. The invention consists principally in arranging the sheets with their edges spaced apart and secured together and to a third member by a weld in contact with 25 all three. It also consists in the parts and in the combinations and arrangements of parts hereinafter described and claim.

In the accompanying drawings, wherein like reference numerals refer to like parts wherever 30 they occur,

Fig. 1 is a plan view of a portion of a car roof embodying my invention,

Fig. 2 is a vertical transverse section through one-half of the roof on the line 2—2 in Fig. 1,
35 Fig. 3 is a vertical longitudinal section through a portion of the roof on the line 3—3 in Fig. 1; and

Figs. 4 to 10, inclusive, are sections similar to Fig. 3 showing modified forms of the invention.
40 In the construction illustrated in Figs. 1 to 3, carlines 1 of inverted U-shape extend from side plate 2 to side plate 2 of the car and are secured thereto. The roof sheets 3 are plain imperforate sheets that extend entirely across the car with 45 their side margins resting on the flat upper surface of adjacent carlines. The sheets are arranged with a space intervening between their edges. This space is filled with a weld 4 that unites the edges of the adjacent sheets together and also to the top of the carline. The weld 4 50 is preferably made by means of an electric welding rod of high tensile metal, such as steel. This method of electric welding enables the weld 4 to be built up to any desirable extent, whereby the 55 welding serves to form not only a continuous

tight joint but also contributes greatly to the strength of the structure.

Another important advantage of the construction illustrated in Figs. 1 to 3 is that it dispenses with the need for squaring the sides of the sheets 5 and of shearing them to accurate width; for there are no holes, ribs, flanges, or other features requiring to be matched, as the metal weld will fill whatever space may be left between the edges of the sheets.

In the construction illustrated in Fig. 4, the roof sheets 5 extend from side plate to side plate of the car and have simple upstanding flanges 6 along their side margins. Between these upstanding flanges is a thick flat strip 7 of metal 15 which serves as a reinforcement or carline member. The flanges 6 of adjacent sheets contact flatwise with the member 7 with the upper edges of the two flanges and the interposed member substantially flush with one another. The 20 flanges 6 and the interposed reinforcing member 7 are welded together by means of a single weld 8 whose bottom is in contact with the edges of the two flanges and the reinforcing member. Preferably this weld is made by means of an 25 electrical welding rod of high tensile metal and the weld is built up so as to have a considerable cross-sectional area and thereby contribute 30 greatly to the strength of the structure.

In the construction illustrated in Fig. 5, the roof sheets 9 are formed with upstanding angular flanges 10 arranged alongside each other but spaced somewhat apart. Such space is bridged by a reinforcing member 11 that contacts flatwise with the underfaces of the flanges; and the 35 two flanges and the reinforcing members are all united together by a weld 12 which fills the space between said flanges and may, if desired, be built up of such cross-sectional area as may be desired to contribute to the strength of the structure. Fig. 6 shows a similar construction where- 40 in the weld 12a serves as a securing means for an upper series of sheets 9a as well as a means for securing the edges of the upstanding angular flanges of the lower series of sheets together and 45 to the reinforcing member.

Fig. 7 shows a joint uniting together vertically disposed flange members 10a and a backing or reinforcing member 11a set vertically edgewise. The construction illustrated in Fig. 8 shows a 50 similar joint embodied in a roof of the so-called neutral axis type, wherein the roof metal is arranged to form panels 12 at an upper elevation united to panels 13 at a lower elevation. In such 55 construction, the web or portion 14 that con-

nects the upper and lower panels 12 and 13 operates mainly to take care of shear stresses, which are of maximum intensity midway between such panels, and is strengthened by a backing or reinforcing member 15. The construction illustrated in Fig. 8 has the particular merit of locating the reinforced joint at such point of maximum intensity of the shearing stress, as the welded reinforced joint adds very greatly to the strength of the web. Fig. 9 shows a neutral axis roof wherein the web formed by the cooperating sheet flanges is strengthened by means of a reinforcing member 17 of Z-shaped section arranged with one flange beneath the lower panel 15 and with the other flange beneath the upper panel. A space is left between the edges of the sheet flanges, and a weld 18 fills such space and serves to secure the flanges together and to the web of the Z-member after the manner shown 20 in Figs. 6 and 7.

The construction illustrated in Fig. 10 shows a carline 19 of tubular form with the plain, spaced imperforate roof sheets welded, as at 20, thereto after the manner of Fig. 3. The particular merit 25 of this construction is that it permits the use of tubular carlines with the same facility as those of other shapes.

It is obvious from the foregoing description that the built-up welds add greatly to the 30 strength of the joint and to the structure, that they dispense with the usual punching, squaring and matching of the roof sheets, permit such wide tolerance in width as to make it feasible to use sheets as they come from the mill and 35 make a tighter, better joint and durable roof with great economy of labor and material.

Reference is hereby made to my copending applications Serial No. 659,492 filed March 3, 1933 and Serial No. 27,848 filed June 22, 1935, for subject matter shown but not claimed herein.

What I claim is:

1. A car roof comprising roof sheets arranged with a space between the side margins of adjacent sheets, a member in contact with the margins of the sheets on opposite sides of such space, and a continuous weld of added metal uniting the edges of adjacent sheets to each other and to said member, said added metal being in substantial excess of the amount required to make the weld and of sufficient cross-sectional area and so located as to substantially increase the strength of the roof.

2. A car roof comprising plain roof sheets arranged with a space between the side margins of adjacent sheets, a member in contact with the margins of the sheets on opposite sides of such space, and a built-up weld of high tensile metal uniting the edges of adjacent sheets to each other

and to said member, said high tensile metal being in substantial excess of the amount required to make the weld and of sufficient cross-sectional area and so located as to substantially increase the strength of the roof.

3. A car roof comprising roof sheets arranged with a space between the side margins of adjacent sheets, and a continuous weld of high tensile metal filling such space and uniting the edges of adjacent sheets to each other, said high tensile metal being in substantial excess of the amount required to make the weld and of sufficient cross-sectional area and so located as to substantially increase the strength of the roof.

4. A car roof comprising roof sheets arranged with a space between the side margins of adjacent sheets, a member in contact with the margins of the sheets on opposite sides of such space, and a continuous weld of high tensile metal filling such space and uniting the edges of adjacent sheets to each other and to said member, said high tensile metal being added in substantial excess of the amount required to make the weld.

5. A car roof comprising roof sheets arranged with a space between the side margins of adjacent sheets, a tubular member in contact with the margins of the sheets on opposite sides of such space, and a continuous weld of added metal filling such space and uniting the edges of adjacent sheets to each other and to said tubular member, said added metal being in substantial excess of the amount required to make the weld and of sufficient cross-sectional area and so located as to substantially increase the strength of the roof.

6. A car roof comprising roof sheets with their edges spaced apart, reinforcing members and continuous welds of high tensile steel uniting the edges of adjacent sheets together and to the reinforcing members, said high tensile metal being in substantial excess of the amount required to make the weld and of sufficient cross-sectional area and so located as to substantially increase the strength of the roof.

7. A car roof comprising roof sheets and reinforcing members of inverted channel shape, said sheets overlapping the tops of the reinforcing members with their edges spaced apart and continuous welds of added metal filling the spaces and uniting the sheets together and to the reinforcing members, said added metal being in substantial excess of the amount required to make the weld and of sufficient cross-sectional area and so located as to substantially increase the strength of the roof.

CHARLES DAVID BONSALL.
